CHALCONE DICHLORIDE AND INSECTICIDAL COMPOSITIONS THEREOF

Samuel F. Clark, University, Miss.

No Drawing. Application December 20, 1951,
Serial No. 262,659

4 Claims. (Cl. 167—30)

This invention relates to chalcone dichloride and certain of its derivatives. It is directed particularly to a new class of compounds which is toxic to living matter, such as fungi and insects, and suitable for use as economic poisons.

The insecticidal value of chlorinated hydrocarbons is well recognized. One of the most widely known members of this group is 2,2-di(4-chlorophenyl)-1,1-trichloroethane (hereinafter referred to as DDT). Furthermore, some species of insects develop a remarkable resistance to some of these chlorinated hydrocarbons.

In attempting to solve the problem of increased insect resistance it has been claimed that the combination of certain chlorinated hydrocarbons with other compounds is more effective than the respective chlorinated hydrocarbons alone. Such compounds include carbinols, esters, ethers, hydrocarbons, chlorinated hydrocarbons and unsaturated ketones.

One of the objects of the present invention is to make available a new class of useful compounds. Another object of the invention is to provide compounds which are useful as toxicants for living matter, such as fungi and insects. A further object of the invention is to provide new compounds with characteristics such that they disrupt the normal metabolic processes of living organisms, thereby having a toxic effect directly, or so change the resistance of the organisms so that other toxic materials may become effective.

This invention is directed to the making and using of chlorinated aromatic ketones containing the special grouping:

suitably enclosed by unsubstituted, or substituted, aromatic rings, which, in summation, render the members of the class effective as economic poisons. Such aromatic rings and alkyl substituted rings include anthryl, furyl, naphthyl, phenanthryl, phenyl, thifuryl, tolyl, xenyl and xylyl groups. R and R' may be either a hydrogen atom or an alkyl group. Certain members of this class of compounds appear to be particularly effective synergists in compositions containing chlorinated hydrocarbons, such as DDT, against strains of insects resistant to such chlorinated hydrocarbons.

More specifically, the present invention is directed to chlorinated aromatic ketones having the general formula

wherein R₁ and R₂ are members of the class consisting of an aromatic ring and a chlorinated aromatic ring, and R₃ and R₄ are members of the class consisting of hydro-

2

gen and an alkyl group. Fourteen compounds representative of this class are:

- 1,3-diphenyl-2,3-dichloro-1-propanone
- 1,3-di(4-chlorophenyl)-2,3-dichloro-1-propanone
- 3-(4-chlorophenyl)-1-phenyl-2,3-dichloro-1-propanone
- 3-(2,4-dichlorophenyl)-1-phenyl-2,3-dichloro-1-propanone
- 3-(2-chlorophenyl)-1-(4-chlorophenyl)-2,3-dichloro-1-propanone
- 10 1,3-di(4-tolyl)-2,3-dichloro-1-propanone
- 1,3-di((4-chlorophenyl)-2,3-dichloro-2-methyl-1-propanone
- 1,3-diphenyl-2,3-dichloro-3-methyl-1-propanone
- 15 1- β -naphthyl-3-phenyl-2,3-dichloro-1-propanone
- 3-(4-chlorophenyl)-1- α -naphthyl-2,3-dichloro-1-propanone
- 3-phenyl-1-p-xenyl-2,3-dichloro-1-propanone
- 3-(4-chlorophenyl)-1-p-xenyl-2,3-dichloro-1-propanone
- 20 3- α -furyl-1-phenyl-2,3-dichloro-1-propanone
- 3-phenyl-1- α -thienyl-2,3-dichloro-1-propanone

The chlorinated aromatic ketones of the present invention without alkyl substituents for hydrogens in the propanone have the general formula

wherein R₁ and R₂ are members of the class consisting of an aromatic ring and a chlorinated aromatic ring. Twelve compounds representative of this classification include all of those listed in the preceding paragraph, except

- 35 1,3-di(4-chlorophenyl)-2,3-dichloro-2-methyl-1-propanone, and
- 1,3-diphenyl-2,3-dichloro-3-methyl-1-propanone

The chlorinated aromatic ketones of the present invention with chlorine substituents in the terminal aromatic rings have the general formula

45 where R₁ is a chlorinated aromatic ring, R₂ is a member of the class consisting of an aromatic ring and a chlorinated aromatic ring, and R₃ and R₄ are members of the class consisting of hydrogen and an alkyl group. Seven compounds representative of this class are

- 1,3-di(4-chlorophenyl)-2,3-dichloro-1-propanone
- 3-(4-chlorophenyl)-1-phenyl-2,3-dichloro-1-propanone
- 3-(2,4-dichlorophenyl)-1-phenyl-2,3-dichloro-1-propanone
- 3-(2-chlorophenyl)-1-(4-chlorophenyl)-2,3-dichloro-1-propanone
- 55 1,3-di(4-chlorophenyl)-2,3-dichloro-2-methyl-1-propanone
- 3-(4-chlorophenyl)-1- α -naphthyl-2,3-dichloro-1-propanone
- 60 3-(4-chlorophenyl)-1-p-xenyl-2,3-dichloro-1-propanone

None of the compounds given in the three preceding paragraphs has been known hitherto, with the exception of the parent compound, chalcone dichloride (1,3-diphenyl-2,3-dichloro-1-propanone). Therefore, each of 65 the new compounds has been prepared for the first time to make it available for testing. The class of compounds for which the general formula and representatives are given in the preceding paragraph include some compounds which have been found to be the most effective synergists with chlorinated hydrocarbons, such as DDT.

One general method for making the compounds of the present invention involves (1) the condensation of un-

substituted or substituted aromatic aldehydes and ketones, or ketones alone, to form unsaturated ketones, and (2) the chlorination of such unsaturated ketones. These process steps are illustrated by the following equations:

The condensations may be effected with basic catalysts, such as alcoholic sodium hydroxide or sodium ethylate, or by acidic catalysts, such as dry hydrogen chloride or boron trifluoride, in the presence or absence of solvent. The preferred temperature range is from 20° C. to the boiling point of the solvent, which is frequently ethanol (B. P. 78° C.), although temperatures up to that of the lowest boiling reactant are desirable in certain cases. The reactions are carried out most advantageously at atmospheric pressure, or moderately above for larger scale production. The products may be recovered by precipitating them on pouring the reaction mixture into water or by vacuum evaporation of the unreacted starting materials. Neutralization of the catalyst may be effected before either of the recovery operations is undertaken. Purification may be accomplished by alcohol and water washing.

The chlorination step is performed preferably by dissolving the unsaturated aromatic ketone in a suitable solvent, such as acetic acid, benzene or chloroform, and then passing chlorine into the solution until the unsaturated ketone has been substantially completely saturated. The preferred temperature range is from 0° C. to the boiling point of the solvent with the pressure usually employed being slightly greater than atmospheric pressure. The recovery of the product is obtained by evaporation of the solvent or, in the case of a water-soluble solvent, by precipitation with water.

Examples illustrating the method for preparing representative members of the class of compounds of the present invention are given below.

Example I

A mixture of 1130 g. (8.1 moles) of p-chlorobenzaldehyde and 1251 g. (8.1 moles) of p-chloroacetophenone was poured with shaking into a 12-liter round bottom flask containing 36 g. of sodium hydroxide dissolved in 300 ml. of water and 70 ml. of ethanol. The mixture became hot, and solidification took place in about 15 minutes. After standing 48 hours, the solid mass was treated with 1000 ml. of water and was then broken up. The suspension was neutralized with dilute hydrochloric acid and was filtered. The solid product was washed with water, with a 50% aqueous solution of ethanol, and again with water. The air-dried crude 4,4'-dichlorochalcone weighed 2195 g. (95.5% yield). A sample recrystallized from ethanol melted at 154-6° C.

A solution of 47 g. (0.13 mole) of recrystallized 4,4'-dichlorochalcone in 950 ml. of chloroform was placed in a 3-neck flask equipped with a sparger tube for chlorine admission, a thermometer, and a reflux condenser, which in turn was connected to a water bubbler to keep the system under a pressure of three inches of water. Chlorine was passed in at a moderate rate over a period of 24 minutes until saturation was achieved. The color of the solution changed from a light yellow to the characteristic yellowish-green of chlorine solutions when saturation was complete. The temperature rose from 23° to 39° C. 75

during the addition of the chlorine. The condenser was reset for distillation, the sparger tube was removed and replaced with a stopper. The distillation was interrupted when the collected distillate reached a volume of 870 ml. (boiling range, 47° to 62° C.) and 90 ml. of ethanol was added to the colorless residual solution. Upon cooling and filtering, a yield of 45.5 g. (77.1%) of 1,3-di(4-chlorophenyl)-2,3-dichloro-1-propanone, white crystals with M. P. 144-5° C., was obtained. An additional quantity of light yellow, partially solidified substance was obtained on evaporation of the filtrate to dryness. However, the weight of this second fraction brought the total yield to more than 100%, indicating the retention of solvent in the second fraction.

15 An alternate method of chlorination was employed in which 3.2 g. (0.015 mole) of 4,4'-dichlorochalcone was dissolved in 80 ml. of glacial acetic acid. Chlorine was passed into the solution in a slow stream for one hour. The solution was poured into water, and 2.1 g. (47.8% yield) of 1,3-di(4-chlorophenyl)-2,3-dichloro-1-propanone was recovered. This compound melted at 133-6° C. and was apparently stereoisomeric with the compound prepared by the preceding chlorination procedure. No difference in the insecticidal activity was noted between 20 the two forms in subsequent tests.

Example II

Using the procedure of Example I, 28.1 g. (0.2 mole) of p-chlorobenzaldehyde was condensed with 24 g. (0.2 mole) of acetophenone in the presence of 6 g. of sodium hydroxide dissolved in 40 ml. of water and 20 ml. of ethanol. The yield of 4-chlorochalcone (M. P. 108-11° C.) was 42 g. (86.2%). A 10-g. sample of this intermediate was dissolved in 30 ml. of chloroform, and the solution saturated with chlorine. A yield of 5.3 g. (41%) of 3-(4-chlorophenyl)-1-phenyl-2,3-dichloro-1-propanone (M. P. 158-61° C.) was obtained.

Example III

40 Using the procedure of Example I, 35 g. (0.2 mole) of 2,4-dichlorobenzaldehyde was condensed with 24 g. (0.2 mole) of acetophenone in the presence of 6 g. of sodium hydroxide dissolved in 40 ml. of water and 20 ml. of ethanol. The yield of 2,4-dichlorochalcone (M. P. 62-5° C.) was 35 g. (63.1%). A 10-g. sample of the chalcone was dissolved in 50 ml. of chloroform, and the solution saturated with chlorine. A yield of 4.6 g. (37%) of 3-(2,4-dichlorophenyl)-1-phenyl-2,3-dichloro-1-propanone (M. P. 99-101° C.) was obtained.

Example IV

45 Using the procedure of Example I, 45.7 g. (0.325 mole) of o-chlorobenzaldehyde was condensed with 50.3 g. (0.325 mole) of p-chloroacetophenone in the presence of 6 g. of sodium hydroxide dissolved in 50 ml. of water and 25 ml. of ethanol. The yield of 2,4'-dichlorochalcone (M. P. 78-80° C.) was 80 g. (88.3%). A 10-g. sample of this chalcone was dissolved in chloroform and chlorinated. A yield of 5.6 g. (45.9%) of 3-(2-chlorophenyl)-1-(4-chlorophenyl)-2,3-dichloro-1-propanone (M. P. 101-4° C.) was obtained.

Example V

50 Using the procedure of Example I, 24 g. (0.2 mole) of p-tolualdehyde was condensed with 26.8 g. (0.2 mole) of p-methylacetophenone in the presence of aqueous-alcoholic solution of sodium hydroxide. The yield of pale yellow, crystalline 4,4'-dimethylchalcone (M. P. 128-9° C.) was over 80% of theoretical. A sample of this chalcone was dissolved in chloroform, and the solution was saturated with chlorine. A white crystalline solid, 1,3-di(4-tolyl)-2,3-dichloro-1-propanone, was obtained as the product (M. P. 132-4° C.).

Example VI

75 Using the procedure of Example I, 14 g. (0.1 mole) of

p-chlorobenzaldehyde was condensed with 16.8 g. (0.1 mole) of p-chloropropiophenone in the presence of sodium ethylate in ethanolic solution. The 4,4'-dichloro- α -methylchalcone obtained was dissolved in chloroform and chlorinated to give a white, crystalline solid, 1,3-di-(4-chlorophenyl)-2,3-dichloro-2-methyl-1-propanone.

Example VII

Dypnone, produced from acetophenone by the procedure of Example I with sodium methylate as the catalyst, was chlorinated in chloroform solution to yield dypnone dichloride, or 1,3-diphenyl-2,3-dichloro-3-methyl-1-propanone.

Example VIII

Using the procedure of Example I, 10.6 g. (0.1 mole) of benzaldehyde was condensed with 17 g. (0.1 mole) of methyl β -naphthyl ketone in the presence of sodium hydroxide in aqueous-alcoholic solution. The product, α -benzal-2-acetonaphthone, was isolated as red-gold crystals (M. P. 105-6° C.). A sample of the latter was dissolved in chloroform and chlorinated to a white solid, 1- β -naphthyl-3-phenyl-2,3-dichloro-1-propanone.

Example IX

Using the procedure of Example I, 14 g. (0.1 mole) of p-chlorobenzaldehyde was condensed with 17 g. (0.1 mole) of methyl α -naphthyl ketone in the presence of sodium hydroxide in aqueous alcoholic solution. The product was a golden crystalline solid, α -(p-chlorobenzal)-1-acetonaphthone. A sample of the unsaturated ketone was chlorinated in chloroform solution to yield a white, crystalline solid, 3-(4-chlorophenyl)-1- α -naphthyl-2,3-dichloro-1-propanone.

Example X

Using the procedure of Example I, 10.6 g. (0.1 mole) of benzaldehyde was condensed with 19.6 g. (0.1 mole) of p-phenylacetophenone in the presence of alcoholic potassium hydroxide to give yellow crystals of 4-phenylchalcone (M. P. 155-6° C.). A sample of the latter was dissolved in chloroform and chlorinated to give 3-phenyl-1-p-xenyl-2,3-dichloro-1-propanone.

Example XI

Using the procedure of Example I, 14 g. (0.1 mole) of p-chlorobenzaldehyde was condensed with 19.6 g. (0.1 mole) of p-phenylacetophenone in the presence of sodium ethylate to yield 4-chloro-4'-phenylchalcone. A sample of the chalcone was chlorinated in chloroform solution to yield a white solid, 3-(4-chlorophenyl)-1-p-xenyl-2,3-dichloro-1-propanone.

Example XII

Using the procedure of Example I, 9.6 g. (0.1 mole) of furfural was condensed with 12 g. (0.1 mole) of acetophenone in the presence of aqueous alcoholic sodium hydroxide to yield an oil, furfurylideneacetophenone (B. P. 315-8° C. at 760 mm.). This intermediate was dissolved in chloroform and chlorinated to yield 3- α -furyl-1-phenyl-2,3-dichloro-1-propanone.

Example XIII

Using a modification of the procedure of Example I, 10.6 g. (0.1 mole) of benzaldehyde was condensed with 12.6 g. (0.1 mole) of methyl α -thienyl ketone in the presence of dry hydrogen chloride to yield styryl α -thienyl ketone (M. P. 79-80° C.). A sample of the latter was chlorinated in chloroform to give 3-phenyl-1- α -thienyl-2,3-dichloro-1-propanone.

The toxicants of the present invention may be prepared and dispersed in comminuted form with or without inert diluents and/or wetting or spreading agents, or dispersed in a suitable medium either in the form of an emulsion or in solution of a suitable solvent or mixture of solvents. The lower melting point members of this class of chlorin-

ated aromatic ketones, that is, with melting points of the order of 100° to 125° C., may be used as fumigants as well as contacticides.

DDT is one of the chlorinated hydrocarbons which has been in general use for a sufficient number of years to observe that certain insects, such as the domestic fly *Musca domestica*, develop strains which have become almost completely resistant to the action of DDT.

One possible solution of the problem of increased 10 resistance to toxic effect is to substitute the newer chlorinated hydrocarbons as contacticides for DDT-resistant house flies. One of the newer insecticides from the standpoint of use by the general public is lindane, 1,2,3,4,5,6-hexachlorocyclohexane, which is not only a powerful 15 insecticide but also a persistent fumigant. However, this substitution procedure has not been too satisfactory since certain strains of insects were initially resistant, or very rapidly developed resistance to the newer toxicants.

Certain tests made to determine the toxicity of the new 20 class of chlorinated aromatic ketones of the present invention, particularly to ascertain both qualitatively and quantitatively the response of the house fly, *Musca domestica*, to a mixture of the respective compound with DDT are represented by the examples given below.

25

Example XIV

One series of tests was made on a strain of DDT-resistant flies, *Musca domestica*: Roberd, by observing the 30 effect of topical application of a solution of the compound indicated and DDT in an inert solvent. Each fly was anesthetized with carbon dioxide, a drop of the toxicant solution was supported on a small-wire loop, and a small amount of the solution was applied directly on the back 35 or thorax of the fly. Approximately 50 flies were used for each test, and the female mortality was recorded.

40	Compound with DDT in solution	Relative Activity, Percent
	1,3-diphenyl-2,3-dichloro-1-propanone	100
	1,3-di(4-chlorophenyl)-2,3-dichloro-1-propanone	303
	3-(4-chlorophenyl)-1-phenyl-2,3-dichloro-1-propanone	106
45	3-(2,4-dichlorophenyl)-1-phenyl-2,3-dichloro-1-propanone	166
	3-(2-chlorophenyl)-1-(4-chlorophenyl)-2,3-dichloro-1-propanone	81

Example XV

50 Another example of the effect on DDT resistant flies is given for a mixture of DDT and 1,3-di(4-chlorophenyl)-2,3-di-chloro-1-propanone present in a 10:1 ratio. The two materials were dissolved in methyl ethyl ketone, the solution was applied to poster boards in such a manner as 55 to provide a residual coating of 200 mg. and 20 mg. per square foot, respectively, and the residual coating allowed to age for one week. The flies were exposed to the toxicants on the poster boards for two hours and then observed after a period of 24 hours had elapsed. The 60 adult female mortality was 92% for the combination as compared with 0% in the case of the control (DDT residue only but otherwise identical conditions).

65

65 A further example of the effect on DDT resistant flies is given for various ratios of DDT and 1,3-di(4-chlorophenyl)-2,3-dichloro-1-propanone by contact with older residual deposits. Solutions of the two materials in appropriate proportions were applied to the plywood walls 70 of respective test cages in such a manner as to provide residual deposits of 200 mg.:200 mg., 200 m.:40 mg., and 200 mg.:20 mg. per square foot, respectively. After a four-week aging of the deposits and a 30-minute 75 exposure of the flies to the aged deposits, the adult fly

mortalities at the end of the 24-hour period after exposure were observed and recorded.

DDT-Compound Ratio, mg./sq. ft.	Fly Mortality, Percent	
	Male	Female
200:200	100	100
200:40	97	86
200:20	100	95

The mortality in the case of the controls with DDT residue only (but otherwise identical conditions) was negligible.

The series of compounds described above was developed as a group of insecticides with effective patterns of structure and reactive functional groups. The structure of the unchlorinated, unsaturated ketones is similar to that of chalcone, its naturally occurring derivatives—the polyhydroxychalcones, and its related classes—the flavones and the flavonols. Saturated ketones of similar structure, the flavanones, are also known to occur in nature. Suitable modification of these basic structures so familiar in nature by the introduction of potential reactive centers may be deleterious to the normal enzyme systems of insects.

It is now generally recognized that certain insects develop resistance to the lethal action of chlorinated hydrocarbons, and that this resistance, though developed against one chlorinated hydrocarbon, is nevertheless effective toward others. The process of detoxifying DDT, in the case of house flies, is apparently one of dehydrohalogenation to form 2,2-di(4-chlorophenyl)-1,1-dichloroethene, a compound isolated in significant quantity from the bodies of resistant strains of flies exposed to DDT.

The effectiveness of the present series of chlorinated aromatic ketones with the chlorinated hydrocarbon, DDT, indicates their potential effectiveness when used with other toxicants, such as aldrin, chlordane, dieldrin, lindane and toxaphene.

Furthermore, the characteristics of the present series of chlorinated aromatic ketones are such that their manner of use, either alone or in combination with other toxicants, includes all typical methods for the applications of insecticides, such as solutions and emulsions for brushing or spraying, dry powders for dusting, wettable powders for preparing emulsions and suspensions, and distribution as a fumigant.

In the classification of the groups of organic compounds described and claimed, the applicant has adopted one of the well-recognized classifications as set forth by Gilman in his *Organic Chemistry*, vol. I, 52-149 (1938). In chapter 2, *Theory of Structure and Reactions of Aromatic Compounds*, the term "aromatic compounds" includes benzenoid rings and heterocyclic rings exhibiting aromatic character, and specifically includes pyridine, pyrrole, thiophene, pyrazole and furan.

10 The present invention is directed generically to compounds consisting of and compositions of matter comprising alpha, beta-dichloropropanones containing aromatic substituents in the 1,3-positions.

In the respective species described and claimed, the aromatic substituents are:

1. Unsubstituted and chloro- and alkyl-substituted benzene rings.
2. Unsubstituted and chloro- and alkyl-substituted benzene rings together with alkyl substituents on the side chain.
3. Unsubstituted and chloro- and alkyl-substituted naphthyl or biphenyl rings.
4. Unsubstituted and chloro- and alkyl-substituted heterocyclic rings.

25 The term "economic poisons" as used in the description and claims is directed specifically to insecticides, fungicides and fumigants. The use of the term in the claims makes it possible to eliminate possible objection to alternatives and multiplicity of claims.

30 I claim:

1. An economic poison comprising 1,3-di(4-chlorophenyl)-2,3-dichloro-1-propanone.
2. An insecticide comprising a chlorinated insecticidal hydrocarbon and 1,3-di(4-chlorophenyl)-2,3-dichloro-1-propanone.
3. An insecticide comprising 2,2-di(4-chlorophenyl)-1,1,1-trichloroethane and 1,3-di(4-chlorophenyl)-2,3-dichloro-1-propanone.
4. 1,3-di(4-chlorophenyl)-2,3-dichloro-1-propanone.
